CLAIM

The ornamental design for a recessed round luminaire, as shown and described.

DESCRIPTION

FIG. 1 is a bottom view of a first embodiment a recessed round luminaire, showing our new design;

FIG. 2 is a bottom perspective view thereof;

FIG. 3 is a bottom view of a second embodiment of a recessed round luminaire, showing our new design;

FIG. 4 is a bottom perspective view thereof;

FIG. 5 is a bottom view of a third embodiment of a recessed round luminaire, showing our new design;

FIG. 6 is a bottom perspective view thereof;

FIG. 7 is a bottom view of a fourth embodiment of a recessed round luminaire, showing our new design;

FIG. 8 is a bottom perspective view thereof;

FIG. 9 is a bottom view of a fifth embodiment of a recessed round luminaire, showing our new design; and,

FIG. 10 is a bottom perspective view thereof.
